SWITCH OPERATING DEVICE

Samuel N. Small, Valley Stream, N.Y., assignor of one-fourth to Albert A. Boccio, Garden City, one-fourth to Milton Spinner, Kew Gardens Hills, and one-fourth to David Slavin, Brooklyn, N.Y.

Application November 15, 1957, Serial No. 696,791

4 Claims. (Cl. 200—153)

This invention relates to devices for operating a switch controlling a circuit of any type or kind by two directional operation of the device so that the device can be operated by two different members or a single member which is moved in two directions. More particularly, the invention deals with a device of the character described, comprising a cam-like switch actuating element, to which is fixed an operating member in the form of a finger or rod.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side view of a device made according to my invention, showing a switch mounted therein, with part of the construction broken away.

Fig. 2 is a section substantially on the line 2—2 of Fig. 1, with part of the structure shown in elevation.

Fig. 3 is a front view of a modified form of device, with parts of the construction broken away.

Fig. 4 is a side view of the structure as shown in Fig. 3, with parts of the construction broken away; and

Fig. 5 is a plan and sectional view of the device shown in Figs. 3 and 4.

In practice, I provide a switch operating device comprising a bracket or supporting frame 10 which, in the construction shown, has spaced bearing portions 11 and 12 joined by an apertured crosshead and mounting plate portion 13, part of the apertures being indicated in dotted lines at 14. A switch of any type and kind 15 is suitably mounted in connection with the crosshead 13, so as to dispose the switch button 16 within the space disposed between the bearings 11 and 12 substantially as shown. The switch 15 has two or more terminals 17, with which circuit wires to a suitable electrical device to be controlled by the switch are coupled.

Mounted in the bearings 11 and 12 is an operating member 18, comprising a rod end 19 supported in the bearings and retained against displacement therefrom by two key pins or the like 20 adjacent the bearing 12. The member 18 also includes an angularly extending finger or rod 21, which is adapted to be actuated by the articles or parts controlled by the switch, which articles or parts are capable of movement in two directions, as indicated by the arrows 22 and 23 in Fig. 2 of the drawing.

Fixed to the rod 19, substantially centrally between the bearings 11, is a switch actuating cam element 24, preferably of plastic material. One end of the element has a large disc portion 25, upon one surface of which is the cam portion 26 of the element, the cam portion being formed by cutting away a surface of the element 26, as indicated at 27, so that, in the normal position of the device, the button 16 of the switch will be clear of the surface 27, as clearly noted in Fig. 2 of the drawing.

A torsion coil spring 27 is mounted on the rod 19 between the disc 25 and bearing 11 and has ends fixed

2

in the bearing 11, as indicated at 28, and in the disc 25, as indicated at 29. The spring 27 normally maintains the element 24 in the position shown in Fig. 2, in which position the rod 21 can, for example, be arranged in axial alignment with the axis of the switch.

The circuit controlled by the switch 15 may be a normally open circuit, in which event, the actuation of the element 24 will close the circuit or it can be the normally closed circuit, whereupon, actuation of the element 26 will operate to open or break the circuit. Operation of the device will be readily understood from the foregoing description and the following statement.

In some uses of this type and kind, two different moving parts can operate upon the rod 21 to control actuation of the switch. In other words, one part can be movable in the direction of the arrow 22 and the other part can be movable in the direction of the arrow 23. In some instances, however, a single member might have two means spaced thereon for operative engagement with the rod 21 so that, at predetermined limits of travel, the rod 21 will be actuated to, in turn, operate the switch in control of the circuit.

It will be apparent that, in movement of the rod 21 in the direction of the arrow 22, the cam portion 30 will actuate the button 16 to move the same inwardly and control the circuit of the switch 15; whereas, movement of the rod 21 in the direction of the arrow 23 will bring the cam surface 31 into operative engagement with the button 16 to accomplish the same result. The degree of movement of the rod 21 in either of these directions can be through an arc of 45° to greater than 180° in either direction.

It will also be apparent, however, that, in some instances, and with the type of switch employed, the degree of movement of the member 18, or the finger or rod 21 thereof, can be reasonably slight, particularly when sensitive type of switch devices are employed. In this connection, it will be apparent that the cutaway surface 27 functions as part of the cam surfaces 30, 31. To illustrate one adaptation and use of the invention, a switch device of the type and kind under consideration can be utilized in actuating a light built upon the opening of a closet door, the device assuming the normally inoperative position shown in the drawing, when the door is in closed or substantially closed position. It will be apparent, however, that many varied uses can be given to the switch device in controlling circuits of any type or kind.

In Figs. 3 to 5, inclusive, I have shown another adaptation of my invention, in which 32 represents a supporting plate having, fashioned from the material thereof, outwardly extending bearings 33 for an operating rod 34, generally similar to the rod 19, except that the rod 34 is tubular in form.

The lower end of the rod has an extending portion 35 flattened and shaped to form a more or less L-shaped foot 36 at its free end, this end being generally similar to the end 21 of the rod 19.

Supported upon the upper end of the plate by suitable bolts or rivets 37 is a switch block 38 of suitable insulating material, having a round bore 39 opening through one end of the block. Mounted on one of the bolts or rivets 37 and insulated therefrom by a sleeve 40 are a pair of spring contacts 41, 42 having coupling ends, which protrude beyond the block for attachment of circuit wires therewith, as diagrammatically illustrated.

Movably supported in the block 38 is a switch operating button 43, the head 44 of which is disposed in the bore 39 and normally positioned adjacent the contact 41. The contacts have contact points 41', 42' on adjacent surfaces thereof, as clearly seen in Fig. 5 of the drawing, so that, in moving the button 43 inwardly, as later described, the points 41', 42' will be moved into

operative engagement to complete the circuit through the contacts.

An insulating sleeve 45 spaces the contacts one from another in their mounting on the sleeve 40 and the contacts are such as to fit snugly in the bore 39, as noted in Fig. 4, thus checking lateral separation of the contacts.

Also mounted on the rivets or bolts 33 are spacing bushings 46 and 47, the bushings 46 being of two parts to provide a space therebetween to receive one hooked end 48 of a spring 49, as clearly noted in Fig. 5 of the drawing.

The other end 50 of the spring is coupled with an offset V-shaped portion 51 at the terminal end 52 of another heavier spring 53 arranged in the upright portion of the tubular rod 34. The lower end of the spring 53 extends downwardly in a straight portion 54, having an outwardly offset end 55 which is arranged in an aperture 56 in the tube 34, the end 55 serving to support the rod 34 against downward movement in the bearings 33.

Upward movement of the rod 34 in the bearings 33 is checked by arrangement of the block 38 to overlie the upper end of the rod where it is arranged in the uppermost bearing 33, as noted at 38' in Fig. 4 of the drawing.

Now considering Fig. 5 of the drawing, the parts are here shown in their normal or inoperative position with the rod end 35 extending substantially at right angles to the plate 32. It will, thus, be seen that, in movement of a door or other object to be controlled by the switch, in the direction of the arrow 57 of Fig. 5, the rod 34 will be rotated in a clockwise direction, increasing the tension on the spring 53 to the point where the end 52 will be moved against the action of the spring 49, until it passes a dead center position; whereupon, the spring 49 will suddenly move the end 52 of the spring beyond this dead center position, until the end 52 assumes a position substantially as indicated by the dot-dash line 58 of Fig. 5, causing the end 52 or the portion 52' thereof, as noted in Fig. 3 in dotted lines, to strike the button 43 and force the same into the box 38 to complete contact between the points 41', 42' and tensionally retain these points in closed circuit position, until such time as the rod 34 is freed; whereupon, the spring 35 will operate to again snap the end 52 back into the full line position of Fig. 5, freeing the button 43 and the spring tension of the contact 41 will result in separation of the points 41', 42'. The portion 52' may be defined as a switch actuating element.

The switch structure, as shown in Figs. 3 to 5, inclusive, is a one-way actuation switch, rather than the double action-type, as noted in Figs. 1 and 2 of the drawing.

The snap action provided by the structure shown in Figs. 3 to 5, inclusive, is desirable in many types and kinds of installations over an action of the type and kind illustrated in Figs. 1 and 2 of the drawing.

The supporting plate, including the bearings 33, may be said to comprise a frame and the block, with its associated parts, namely the contacts 41, 42 and button 43, will comprise a switch which is mounted in the frame. Further, the end 52, 52' of the spring 53 may be said to comprise a switch actuating element by reason of the fact that operation of the rod 34 directly controls move-

ment of 52, 52' into the switch operating position and the rod constitutes means projecting from the casing for actuation of said element.

Having fully described my invention, what I claim as new and desire to secure by Letters Patent is:

1. A switch device comprising a frame, a circuit controlling switch mounted in the frame, a switch actuating element rotatable in the frame, spring means controlling operation of said element and normally supporting the element in inoperative position with respect to said switch, means projecting from the frame for actuating said element in movement of the element into switch actuating position, said last named means including a tubular portion supported in spaced bearings in the frame, said

10 element in inoperative position with respect to said switch, means comprising a coil spring mounted in said tubular portion and having an integral end protruding from the tubular portion and forming said switch actuating element, and a second coil spring supported in the frame and coupled with said element to normally support the element in inoperative position and in retention of the element in the circuit closing position of said switch.

2. A switch device comprising a frame having spaced integral bearings, a circuit controlling switch mounted in

25 the frame, a rod rotatable in said bearings, a switch actuating element operated by said rod, means supporting the element in inoperative position with respect to said switch, said rod having an integral radial extension, whereby said rod may be actuated in movement of said element into position to actuate said switch, tensional means controlling operation of said element, said rod including a tubular portion arranged in said bearings, and said tensional means comprising a coil spring mounted in said tubular portion and having an integral end protruding from said tubular portion and forming said switch actuating element.

3. A device as defined in claim 2, wherein the other end of said coil spring, in conjunction with said switch, retains the tubular portion against displacement from the bearings of said frame.

4. A switch device comprising a frame having spaced integral bearings, a circuit controlling switch mounted in the frame, a rod rotatable in said bearings, a switch actuating element operated by said rod, means supporting the element in inoperative position with respect to said switch, said rod having an integral radial extension, whereby said rod may be actuated in movement of said element into position to actuate said switch, tensional means controlling operation of said element, said rod including a tubular portion arranged in said bearings, and said tensional means comprising a coil spring mounted in said tubular portion and having an integral end protruding from said tubular portion and engaging one of said bearings in retaining the parts in assembled relationship.
